UNITED STATES PATENT OFFICE.

WILLIAM F. WILLIAMS AND HENRY L. WILLIAMS, OF YORK, PENNSYLVANIA.

IMPROVEMENT IN CLOTHES-WRINGERS.

Specification forming part of Letters Patent No. 177,910, dated May 23, 1876; application filed April 15, 1876.

To all whom it may concern:

Be it known that we, W. F. WILLIAMS and HENRY L. WILLIAMS, of York, in the county of York and State of Pennsylvania, have invented a new and valuable Improvement in Clothes-Wringers; and we do hereby declare that the following is a full, clear, and exact description of the construction and operation of the same, reference being had to the annexed drawings, making a part of this specification, and to the letters and figures of reference marked thereon.

Figure 1 of the drawings is a representation of a longitudinal vertical section of my clothes-wringer; and Fig. 2 is a side view of the same.

This invention relates to means for wringing wet fabrics; and the nature of our invention consists in combining with two wringing-rollers two cams or eccentrics, which operate, by means of a crank-handle, to forcibly compress the fabrics passed between said rollers, the cams operating to force the lower wringing-roller upward, and springs acting on levers operating on the upper roller, as will be hereinafter explained.

In the annexed drawings, A A designate the cheeks of the wringer, and B B' are the wringing-rollers, between which the fabrics are passed to squeeze the water out of them. The two cheeks A A are constructed with jaws a, and provided with clamping-screws b, by means of which the machine can be secured to a tub. C C are levers, which are connected to the cheeks A A by means of an arched pivot-brace, D, which allows said levers to articulate freely in vertical planes. Between the ends of the levers C and the cheeks A are springs S, which are held in place by studs, or their equivalents. The opposite ends of levers C are scored out and press on

the journals of the upper roller B, and are notched to receive tenons, which are formed on uprights of the cheeks A. This retains the ends of the levers in place against lateral displacement, and allows them free vertical play. The journals of the lower roller B' bear upon blocks g, which are held down upon eccentrics h by the springs S acting on the upper roller B. The two eccentrics h are fixed on a shaft, J, which has its bearings in the cheeks of the machine, and which bears on one end a crank-handle, F. G designates a segmental rack, which is secured to one of the cheeks A concentric to the axis of the shaft J, for the purpose of engaging with the crank-handle F, and retaining the cams in a fixed position when they are properly adjusted.

It will be seen, from the above description, that the springs S, acting through the medium of the levers C, keep a continued elastic pressure on the upper roller B, which pressure can be increased or diminished by adjusting the cams or eccentrics h.

What we claim as new, and desire to secure by Letters Patent, is—

In a clothes-wringer, the cheeks A, with jaws a, and clamping-screws b, and provided with rollers B B', blocks g, and springs S, in combination with the shaft J, having eccentrics h, segmental rack G, and handle F, the whole arranged and operated in the manner and for the purpose set forth.

In testimony that we claim the above we have hereunto subscribed our names in the presence of two witnesses.

W. F. WILLIAMS.
HENRY LEWIS WILLIAMS.
